UNITED STATES PATENT OFFICE.

MARK THOMAS DENNE, OF RUSHDEN, ENGLAND.

SEWING-MACHINE.

1,301,400.

Specification of Letters Patent. Patented Apr. 22, 1919.

Application filed September 22, 1914. Serial No. 863,025.

To all whom it may concern:

Be it known that I, MARK THOMAS DENNE, a subject of the King of Great Britain and Ireland, residing at Rushden, Northamptonshire, England, have invented new and useful Improvements in and Relating to Sewing-Machines, of which the following is a specification.

This invention has reference to improvements in sewing machines of the type known as outsole stitchers, used for stitching the outsole to the welt or to the middle sole of boots or shoes and in which a curved needle and a curved awl are employed, and it comprises the combination with the stitch-forming mechanism of such machines of thread-measuring means controlled by the presser foot and comprising a pivotally-mounted pull-off lever coupled on the one hand to the presser foot and on the other hand to the take-up lever by slotted links to draw off a length of thread for each stitch proportional to the thickness of the work. It also comprises the combination with the stitch-forming mechanism, of a presser foot and means hereinafter described under the control of the operator to control the clamping force of the presser foot and the amount of the lift thereof.

30 An embodiment of my invention is illustrated in the accompanying drawings, in which—

Figure 1 is a side elevation of the head of a machine embodying my invention;

35 Fig. 2 is an end elevation of the presser-foot-actuating means;

Fig. 3 is a side elevation of the same, partly in section;

40 Figs. 4 and 5 are end and side views, respectively, of the thread-measuring means, and

Fig. 6 shows a detail of same.

Referring to the said drawings, 1 indicates the head of the machine and 1^a is a 45 cam shaft on which the necessary cams or cam cylinder for operating the mechanism of the machine are or is mounted in an oil-tight casing 2.

7^a indicates a curved needle which is carried by an oscillating needle stock or segment 7 which is provided with gear teeth that mesh with teeth formed on the end of a needle-operating lever 9, and 8 indicates an oscillating awl stock or carrier 55 which is provided with gear teeth that mesh with teeth formed on an awl-operating lever

10. These levers 9 and 10 are actuated from cams carried by the cam shaft 1^a.

In accordance with the invention the presser-foot or channel guide 28 is carried 60 on an arm of a lever 29 mounted on a sleeve forming part of the needle and awl pivot. The lever 29 gears with a lever 30 carried on a suitable shaft 31 on which a handle is fixed whereby the operator may raise the 65 presser foot 28 to enable him to insert or remove the work. The lever 30 referred to has a second gear segment which meshes with a pinion 33 forming part of or mounted on a shaft 34, on which is also mounted a 70 toothed or ratchet wheel 35 and which shaft is carried by a rocking lever.

On the spindle or shaft 31 on which the handle referred to is mounted and supported in bearings in the machine frame or head 75 and free to rock is a sleeve 36 the said rocking movement of which is derived from a cam lever 38 through the intermediary of a lever 37 mounted on said sleeve. When the sleeve 36 is rocked it imparts movement to 80 a rocking lever 39 in which the spindle 34 carrying the toothed pinion 33 and the ratchet wheel 35 is mounted.

Mounted loosely on the sleeve 36 is a 85 plate 40 carrying two pawls 41, 42 one or other of which may be in engagement with the ratchet wheel 35. Said plate 40 is normally held in its central position by a spring bolt 43 against the action of which the plate 90 may be moved to either side and by which the plate can be returned to its normal position.

By the means described:

(a) the presser foot may be allowed to be free at which time it may be raised by the operator by means of the handle referred to;

(b) the presser foot may be locked and then forcibly clamped on to the work to compress or consolidate the same during the formation of the stitch;

(c) the presser foot may be unclamped and lifted to permit the work feed to operate;

(d) the amount of the clamping action and the degree of "lift" is under the control 105 of the operator.

When the ratchet wheel 35 is in position between the pawls so that neither pawl engages the teeth the operator can raise the presser by means of the handle provided for 110 such purpose. When the arm 39 carrying the ratchet wheel 35 is moved in one di-

rection one of the pawls by engaging the teeth immediately stops the further rotation of said wheel 35 and the pinion 33 and consequently the presser foot operating lever 29 moves to clamp the work and if the motion is arrested at this time the work is clamped firmly. When thereafter the arm 39 is swung in the opposite direction its ratchet wheel 35 will be engaged by the other pawl and the presser-foot in such movement will be raised to a slight extent.

If the motion is, for example half-an-inch "lift" plus one eighth or a quarter of an inch clamping movement and the pawls are set so that they only just make contact at the extremity of each stroke no lifting or clamping can occur, but only locking. It follows therefore that a very simple, efficient and fine adjustment of the degree of clamping and the amount of "lift" is obtainable by merely adjusting the position of the pawls. For example if one pawl (say the right-hand one) is adjusted to be close up to the ratchet wheel 35 so that this almost immediately engages the said ratchet wheel when it is moved to the right, a clamping of approximately one eighth of an inch will result. A similar movement will result if the left hand pawl be similarly adjusted.

The take-up 67 (see Figs. 4 and 5) is mounted upon a rock shaft 68 having at its outer end an extension 69 with which a yoke 70 carried by a lever 71 on a shaft 72 having another and cam operated lever 73 engages.

The thread—shown in dot-and-dash lines—coming from the container or spool at the back of the machine passes over at tensioning wheel 74 and from this to a measuring off roll 75. Said roll is carried on one arm of a ball-crank 79 on one end of a rock shaft 76 which carries at its other end a lever 77 that is connected by a link 78 to a crank pin 82 on the shaft 34. A second link 78^a also connected to said rock shaft 76 has a slotted end fitting a pin 80 on the take-up arm 67. From the measuring off roll 75 the thread passes vertically through a locking device 84, 85 hereinafter described. When the main take-up arm 67 descends to complete the stitch the thread is locked but the link 78^a being operated by the pin 80 pulls upon the ball-crank lever 79 causing a certain length of thread to be drawn off the tension wheel 74 ready for the next stitch.

The length of thread to be measured off is accurately determined by the thickness of the work passing between the presser foot 28 and the table of the machine in the following manner:

The shaft 34 on which the ratchet wheel 35 referred to above is mounted is geared positively with the presser foot carrying lever 29 and when the presser foot owing to an increase in the thickness of the work is farther from the table the said shaft will

also have changed its position and in such a manner that the crank pin 82 controlled by it is made to operate the thread roll 75 through the slotted link 78, lever 77 and a pin 77^a which is carried by the said lever and is engaged in the slot in the said link, to set it in a position corresponding with the thickness of the particular portion of the work on which the presser foot is acting. The arrangement and construction of the parts are such that movement of the roll 75 is not prevented and when therefore the main take-up 67 operates to actuate the roll 75 it only moves the latter for the remainder of the distance representing the difference between the full stroke of the pin 80 on the take-up arm and the amount that the thread roll 75 has been permitted or compelled to rise by the increased thickness of the work and thus the length of thread measured off is strictly proportional to the thickness of the work if the parts are correctly proportioned in the first instance.

The thread is locked when the main take-up is about to act upon it by means of the locking device hereinbefore referred to consisting of a plunger 84 working in a tube 85 one end of which has a slot and an end portion 84^a forming a face 85^a between which and the end of the plunger the thread is clamped. The plunger 84 is actuated to clamp and unclamp the thread by a small lever 88 of approximate inverted T shape pivoted at 89, the cross bar of which lever is engaged at its front end with the plunger 84 and at its rear end with a short lever 90 fixed upon a vertical rock shaft 90^a which carries at its upper end a cam lever 91 provided with a cam roll 91^a that is operated by a cam on the main shaft. I preferably provide a spring 87 which acts upon the lever 88 to maintain the cam lever in contact with its cam.

The auxiliary take-up is carried on a rock shaft having a coil spring to maintain the thread roll 95 in position against the pull of the thread by the main take-up. All the thread controlling apparatus is supported on a bracket 97 and is protected by a hinged door 98 normally held closed by a spring dependent 100.

What I claim as my invention and desire to secure by Letters Patent is:—

1. In a sewing machine, the combination with a work-table, of a presser-foot, stitch-forming mechanism, a take-up lever, and thread measuring means controlled by the presser-foot and comprising a pivotally mounted pull-off lever coupled on the one hand to the said presser foot and on the other hand to the said take-up lever by slotted link to draw off a length of thread for each stitch proportional to the thickness of the work.

2. In a sewing machine, the combination

with stitch-forming mechanism, of a presser foot, thread measuring means, controlled by the presser foot, and means under the control of the operator to control the clamping force of the presser foot and the amount of the lift thereof.

3. In a sewing machine, the combination with a work table and a presser foot carried by a lever which is pivotally mounted 10 on a horizontal axis and has a rearwardly extending arm, of means for raising the said presser foot by hand consisting of a gear segment on the said rearwardly extending arm and an actuating lever pivotally mounted 15 on an axis parallel to the aforesaid axis and provided with a handle and a gear segment which meshes with the aforesaid gear segment, and means for alternately raising and depressing the said presser foot to an 20 adjustable extent automatically, to permit the work to be fed and to exert a clamping force upon the work, the said means consisting of a second gear segment on the aforesaid actuating lever, a sleeve mounted 25 loosely upon the axis of the said actuating

lever, a lever arm fixed to the said sleeve and engaged with a cam operated lever by which the sleeve is oscillated through a fixed arc, a second arm fixed to said sleeve, a shaft rotatably carried by the said second arm, a 30 pinion fixed on the said shaft and in gear with the said second gear segment on the actuating lever, and a locking device comprising a ratchet wheel fixed on the pinion shaft, a plate pivotally mounted on the 35 aforesaid sleeve and normally held in a non-operative position by a spring bolt, and two pawls adjustably mounted on the said plate—one at each side of the said ratchet wheel—and adapted to engage the said 40 ratchet wheel alternately when the said sleeve is oscillated.

In testimony whereof I have signed my name to this specification in the presence of two subscribing witnesses.

MARK THOMAS DENNE.
